UNITED STATES PATENT OFFICE.

CLARENCE L. TAYLOR, OF ALLIANCE, OHIO, ASSIGNOR TO THE MORGAN ENGINEERING COMPANY, OF ALLIANCE, OHIO.

SHAFT-COUPING.

1,149,306.

Specification of Letters Patent.

Patented Aug. 10, 1915.

Application filed April 28, 1914. Serial No. 834,977.

To all whom it may concern:

Be it known that I, CLARENCE L. TAYLOR, of Alliance, in the county of Stark and State of Ohio, have invented certain new and useful Improvements in Shaft-Couplings; and I do hereby declare the following to be a full, clear, and exact description of the invention, such as will enable others skilled in the art to which it appertains to make and use the same.

My invention relates to an improvement in shaft coupling designed particularly for connecting the vibrating spindle and roll in a rolling mill, the object being to provide a connection which will permit of a free wabbling movement of the roll or spindle without any lost motion between the parts, thereby avoiding all pounding incidental to lost motion, in starting and stopping the mill.

20 A further object is to provide a construction wherein the rocking and sliding movement of the coupling members will be smooth and uniform.

A further object is to provide a coupling that can be produced more economically and take up less room both in the direction of the axis of the shaft and at right angles thereto, than any flexible coupling now in use.

30 With these objects in view my invention consists in the parts and combination of parts and in the details of construction as will be more fully explained and pointed out in the claims.

35 In the accompanying drawings, Figure 1 is a view in elevation of my improved coupling; Fig. 2 is a view of the members detached; Figs. 3 and 4 are end views of the coupling members; Fig. 5 is a view in transverse section taken centrally through the coupling and Figs. 6 and 7 are views in longitudinal section, Fig. 6 being taken through the jaws on one coupling member and Fig. 7 through the jaws on the other member.

45 1 represents a spindle and 2 a roll or pinion shaft. If the spindle be provided with couplings at each end, they would be alike. Each part to be coupled is provided with a coupling member 3, one of which has two oppositely located projecting jaws 4 and the other two similarly located jaws 5, the spaces between the jaws being slightly greater than the width of the jaws, so that when they are assembled, ample clearance will be provided

for the vibrating or wabbling movement of the parts.

Each jaw is provided on its inner face with a groove, all of which extend in the direction of the axis of the roll and spindle. The inner walls of grooves 6 in the jaws 4, 60 are formed in the arc of a circle, while the inner walls of the grooves 7 in the jaws 5, may be and preferably are flat and parallel. The jaws of one coupling member intermesh with the jaws of the other member without actual contact, and they are locked together by the knuckle 8, which latter is in the shape of an X, with its jaw engaging members 9 located ninety degrees apart. The outer ends 10 of the jaw engaging members 9, are 70 in the arcs of a circle concentric with the axis or center of the knuckle and also with the inner walls of the grooves 6 in the jaws 4, so that when the knuckle is in place within said jaws it is free to turn therein, or the 75 coupling member can turn on it. The throat of this coupling member 3, intermediate the jaws 4, is curved to conform to the curvature of the inner walls of the jaws, so that there is a continuous guide way, in the arc of a 80 circle, which is greater than a half circle, from the outer end of one jaw to the other. The distance between the outer ends of the jaw 4 is less than the distance between the greatest diameter of a pair of jaw engaging 85 members 9 of the knuckle, hence in order to insert the knuckle within said coupling member, the jaw engaging members 9 which engage said jaws must be entered in the direction of the axis of the coupling member and 90 then turned in a direction for its members 9 to enter the grooves 6, and when so entered and assembled, it will be locked therein and can only be removed by turning the knuckle until the jaw engaging members are in line 95 with the axis of the coupling member, which position is never assumed by the knuckle in the operation of the parts when coupled up.

The other pair of jaw engaging members 9 of the knuckle, have a straightaway sliding fit in grooves 7 in jaws 5 so that the latter may be coupled up to the knuckle carried by the jaws 4 by an endwise movement of either part, and may be uncoupled by a straightaway movement from the knuckle, 100 The knuckle is therefore the part which connects one coupling member to the other, and when the parts are assembled it is inclosed

within the throats of said member, and has a free rocking movement on the knuckle, so that while the two members are locked against independent turning or rotary movement, the universal connection between them permits either to wabble or vibrate without affecting the coupling or the other member and without creating any space which could permit of any lost motion between the parts, and as the knuckle is wholly within the throat of the coupling members, the coupling as a whole is compact and takes up less room both in direction of the axis of the spindle and roll and at right angles thereto, than any coupling now in use. Again as the jaw engaging members of the knuckle have close sliding fit within the grooves, there can be no lost motion consequently all damage due to pounding is avoided.

It is evident that many slight changes might be resorted to in the relative arrangement of parts shown and described without departing from the spirit and scope of my invention. Hence I would have it understood that I do not wish to confine myself to the exact construction and arrangement of parts shown and described but,

Having fully described my invention what I claim as new and desire to secure by Letters Patent, is:—

1. A universal coupling consisting of two members having intermeshing jaws and an integral knuckle having a plurality of engaging members for the jaws of both members, the ends of said engaging members of the knuckle resting in recessed seats formed in the inner faces of the jaws, the seat in one jaw constructed to permit the engaging member to rotate without longitudinal movement and the other seat constructed for both longitudinal and rotary movement of the engaging member, thereby permitting the two coupling members to be disconnected by a straight endwise movement.

2. A universal coupling consisting of two members one of which is provided with a

pair of oppositely disposed jaws each having a recessed inner face, the inner walls of said recesses being in the arc of a circle greater than a half circle, the other coupling member having a pair of oppositely disposed jaws adapted to intermesh with the jaws of said first mentioned member and provided on their inner faces with recessed seats the side walls of which are substantially parallel, and an integral knuckle having an engaging member for each recessed jaw.

3. A universal coupling consisting of two members each having a pair of jaws with recessed inner faces, the inner walls of the recesses in one member and the throat of the latter being in the arc of a circle, and the inner walls of the recesses in the other member being parallel and straight, and an integral coupling having two pairs of jaw engaging members, the ends of one pair being curved to conform to the curvature of the inner walls of said recessed seats.

4. A universal coupling consisting of two members having intermeshing jaws, and an integral knuckle carried by one of said members and having a rocking movement in the jaws thereof, and having a loose sliding connection with the jaws of the other member.

5. A universal coupling consisting of two members having intermeshing jaws and an integral knuckle locked to the jaws of one of said members and having a free turning movement therein and having a loose sliding connection with the jaws of the other member, whereby the two members are locked by the knuckle against independent turning movement, but are free to vibrate or have a wabbling movement independently of the other.

In testimony whereof, I have signed this specification in the presence of two subscribing witnesses.

CLARENCE L. TAYLOR.
